UNITED STATES PATENT OFFICE.

NELSON M. LANGDON, OF MANCELONA, MICHIGAN.

STORAGE-BIN.

1,376,021.

Specification of Letters Patent. Patented Apr. 26, 1921.

Application filed August 25, 1919. Serial No. 319,594.

To all whom it may concern:

Be it known that I, NELSON M. LANGDON, a citizen of the United States, residing at Mancelona, in the county of Antrim and 5 State of Michigan, have invented certain new and useful Improvements in Storage-Bins, of which the following is a specification.

This invention relates to storage bins and 10 has for its object the provision of a strong, durable and inexpensive structure in which coal, grain or other material may be stored and from which the material may be readily withdrawn. A particular object of the invention 15 is to provide a structure whereby a longitudinally traveling overhead bucket or carrier may be utilized to deposit material in the bin or to withdraw the same material and all the material may be withdrawn by 20 the manipulation of the bucket without moving the same transversely or requiring any handling of the material to bring it into the path of the bucket.

The stated objects of the invention and 25 other incidental objects which will appear in the course of the following description are attained in such a mechanism as is illustrated in the accompanying drawings and the invention resides in certain novel features which will be particularly pointed out 30 in the claims following the description.

In the drawings:

Figure 1 is a side elevation of a storage bin embodying my improvements, showing 35 the same located adjacent a railroad track whereby the material may be transferred from the bin directly to a car or vice versa.

Fig. 2 is a vertical transverse section.

In carrying out my invention, I employ a 40 bin or receptacle which may be constructed of any convenient or preferred material and will generally be constructed of concrete or other plastic material which may be molded into the proper form at the location selected 45 for the bin. As shown most clearly in Fig. 2, the sides of the bin converge downwardly, as at 2, and the bottom 3 of the bin is relatively narrow so that only a small portion of the bin will have a flat bottom, the purpose of which will presently appear. The 50 downwardly converging sides 2 may have their upper terminals located at the ground surface 4 or they may be continued in vertically disposed walls 5 to any desired height. 55 The vertical walls will generally be employed inasmuch as the bin will be thereby

given greater capacity without occupying an excessive amount of ground space and a greater quantity of material may be stored within a bin covering a given area. Upon 60 the side walls 2, I provide abutments 6 in which the lower ends of posts 7 may be embedded or otherwise anchored. These posts 7 converge slightly upwardly, as shown in Fig. 2, and are provided at intervals through 65 the entire length of the bin. The posts are disposed at corresponding points on the two sides of the bin and the upper ends of the corresponding posts support transverse beams or caps 8. Bracing plates 9 are secured to the opposite faces of the beam and the posts at the meeting ends thereof, as clearly shown in Fig. 2, so that the beams and posts are rigidly connected and braced against lateral movement and ample space 70 is provided for the scoop or bucket presently described. Upon the outer edges of the posts, I secure rails 10 which extend the entire length of the bin and braces 11 are also secured to the posts and the said rails to lend 75 rigidity to the structure and brace the members against longitudinal movement. Extending longitudinally of the bin, preferably in the central vertical plane of the same, a track 12 is secured to and carried by the 80 beams 8. A carrier including a trolley 13 of any well-known or preferred form is mounted to travel upon the said track 12 and may be controlled by a cable 14 extending from end to end of the structure. The 85 trolley supports a scoop or bucket 15 which is operated in a well-known manner to dump material contained therein into the bin and also to take up or receive material stored in the bin and withdraw the same. 90

In Fig. 2 I have indicated material stored in the bin and it will be noted that its greatest height is in the central vertical longitudinal plane of the bin. The bucket 15 is directly over the apex of the material and 95 will, of course, if lowered, enter the material at its highest point. As the quantity of material in the bin is reduced by successive withdrawals, a central depression, as indicated by the dotted line 16 in Fig. 2, will be 100 formed in the stored material. This depression will continue to deepen centrally as more material is withdrawn. When the base of the depression reaches or passes below the horizontal plane of the top of the bin or 110 of the upper extremities of the downwardly converging side walls 2, the side portions of

the material will gravitate toward the center thereof inasmuch as the converging side walls do not furnish a stable support for the material. The bucket may thus be utilized 5 to withdraw the entire quantity of material from the bin without moving laterally and without requiring the material to be shoveled into the path of the bucket, and to facilitate the taking up of every particle of 10 the material by the bucket or scoop the flat portion 3 of the bottom of the bin will be just wide enough to accommodate the width of the bucket so that the final operation of the bucket will act upon the entire surface 15 of the extreme bottom of the bin and none of the stored material will be left and lost.

It will be readily noted that the same instrumentality which delivers material into the bin is utilized to withdraw the material 20 therefrom and I thereby economize in the cost of installation and also in the cost of operation. The method of operation is also simplified and material may be rapidly stored in the bin until the same is filled to 25 its capacity and when it is desired to withdraw some or all of the material the desired result may be easily and rapidly attained. It will be noted that the supports for the track in the illustrated embodiment of the 30 invention are anchored below the top of the bin and within the same so that the possibility of the supports being damaged by chance blows is minimized. Moreover, this arrangement permits the use of a comparatively large bin or storage receptacle without spreading the posts to such an extent that transverse trusses are needed to brace the structure. A clear space for the bucket 35 from end to end of the bin is provided and the necessity for lateral movement of the bucket is overcome.

It is to be understood, however, that I do not limit myself to the exact details shown in the accompanying drawings but may use 40 any form of structure which will support the track and provide a clear passage for the bucket from end to end of the bin and a cable secured at its ends may be employed instead of the track rails or beams shown. 45 The bucket may be of any well-known or preferred form operable to take up or receive material at one point and carry it to and deposit it at another point.

As previously noted, the drawings illustrate 50 the bin located with one end adjacent a railroad track, thereby expediting the transfer of material from a car to the bin or from the bin to a car. At the opposite end of the bin, a landing or platform may be provided so 55 that material may be transferred from supply trucks or wagons to the bin or from the bin to supply wagons or trucks.

Having thus described the invention, what is claimed as new is:

1. An apparatus for the purpose set forth

comprising an elongated permanent stationary storage receptacle having downwardly converging imperforate side walls, and an overhead container mounted to travel longitudinally of said receptacle from end to 70 end thereof to deliver material thereto or withdraw material therefrom.

2. An apparatus for the purpose set forth comprising an elongated permanent stationary receptacle having downwardly converging imperforate side walls and a relatively narrow flat imperforate bottom connecting the lower extremities of said walls, and an overhead container mounted to travel longitudinally of the receptacle in the vertical 80 plane of said bottom to deliver material thereto or withdraw material therefrom. 75

3. An apparatus for the purpose set forth comprising an elongated permanent stationary receptacle having downwardly converging imperforate side walls, supports anchored upon and rising from said side walls, a track carried by said supports and disposed longitudinally of the receptacle, the space below the track being unobstructed 90 from end to end of the receptacle, and a traveling container supported by said track above the same to deliver material thereto or withdraw material therefrom. 85

4. An apparatus for the purpose set forth 95 comprising an elongated stationary permanent receptacle having downwardly converging imperforate side walls, spaced pairs of posts supported by and rising from the inner surfaces of said side walls, transverse 100 beams connecting the upper ends of opposed posts, a track secured to said beams and disposed in the medial longitudinal plane of the receptacle, and the space defined by and between the posts and the transverse beams 105 being unobstructed from end to end of the receptacle, a traveling container supported by said track to deliver material to the receptacle or withdraw material therefrom.

5. An apparatus for the purpose set forth 110 comprising an elongated permanent stationary receptacle having downwardly converging imperforate side walls, posts rising from the said side walls below the upper ends thereof, beams secured to and extending between the upper ends of corresponding posts at the opposite sides of the receptacle, a track extending longitudinally of the receptacle and secured to the under sides of said beams, the space below the track and 120 between the opposed posts being unobstructed from end to end of the receptacle, and a traveling container supported by said track to deliver material to the receptacle or withdraw material therefrom. 115

6. An apparatus for the purpose set forth comprising an elongated permanent stationary storage bin having downwardly converging imperforate side walls, posts rising from the said side walls at points below the 130

upper edges thereof, braces secured to and connecting the posts on the same side of the receptacle, transverse beams extending over the upper ends of corresponding posts at the 5 opposite sides of the receptacle, bracing plates secured to the ends of said beams and the posts, a track secured to said beams in the vertical plane of the meeting points of the side walls of the receptacle, the space below the track and between the posts being unobstructed from end to end of the receptacle and a traveling container supported by said track to deliver material to the receptacle or withdraw material therefrom.

10 7. An apparatus for the purpose set forth comprising an elongated stationary permanent receptacle having downwardly converging imperforate side walls, a loading

and unloading station at the end of the receptacle, a superstructure providing an open 20 passage above the receptacle from end to end thereof, and a container mounted for travel along the open passage provided by the superstructure to deliver material to the receptacle or withdraw it therefrom. 25

8. An apparatus for the purpose set forth comprising an elongated permanent stationary receptacle having downwardly converging side walls, a fixed track arranged above the receptacle and extending from end to 30 end thereof in the central longitudinal plane thereof, and a container mounted to travel on said track to deliver material to the receptacle or withdraw it therefrom.

In testimony whereof I affix my signature. 35
NELSON M. LANGDON. [L.S.]
